FUEL VAPORIZER AND BURNER

Charles A. French, Riverside, Ill.

Application June 15, 1933, Serial No. 675,932

3 Claims. (Cl. 158—53)

This invention relates to a liquid fuel vaporizer and burner. More specifically it relates to an improved burner and vaporizer construction for handling heavy fuels for blue flame combustion.

The principal object of the invention is to provide for both indirect and direct heating of the fuel to be vaporized by hot products of complete combustion from the burner.

10 Other objects, such as the improved structural features of the vaporizer and burner, will be apparent from the detailed description to follow.

15 The objects of the invention are attained by a construction such as shown in the single figure of the drawing, which shows in cross section a vaporizer and burner.

As illustrated in the drawing, a cylindrical casing 10, closed at both ends, houses a vaporizing chamber 11 spaced from the sides and ends of the casing 10. The upper end of the chamber 11 is open. A cylindrical perforated screen 12 extends between the side walls of the casing 10 and the chamber 11, being connected 20 to both of said members.

25 A vertical shaft 13 extends centrally through the concentrically arranged vaporizing chamber and casing. A pulley 14 on the upper end of said shaft provides means for rotating the shaft. The upper portion of the shaft is formed with a hollow bore 15 for the passage of fuel. A fuel supply conduit 16, provided with an adjustable nozzle 17, is positioned to deliver fuel to the hollow end of the shaft. A distributing disk 18 is mounted on the shaft 13 below the open upper end of the chamber 11. Said disk is curved at its peripheral edge to better distribute the fuel therefrom. The bore 15 in the upper end of the shaft 13 communicates with 30 outlets 19 above the disk 18 for distributing liquid fuel to said disk.

35 The shaft 13 extends downwardly through the bottom of the casing 10 into a fan or pump housing 20 which contains a conventional impeller, not shown, for moving gases. Said housing is provided with an air inlet 21 at its lower side centrally of the housing and a gas inlet 22 at its upper side in the same relative position. The inlet 22 extends upwardly through 40 the bottom of the casing 10 and the bottom of the chamber 11 which is spaced therefrom, into said chamber. A supply chamber 23 provided with a horizontal burner grating 24, is connected by a conduit 25 as an outlet from the housing 45 20. A burned gas collecting member 26 has an

open end covering a portion of the grating 24 spaced vertically thereabove. Said member is connected to the bottom of the casing 10.

5 In the operation of the burner, as above described, fuel admitted to the hollow shaft 13 is distributed on the disk 18 from the edge of said disk radially therefrom as a spray. Said spray impinges the walls of the vaporizing chamber 11 and flows downwardly along the walls. A spark

10 plug 27 mounted in the top of the casing 10, is utilized for initially igniting the spray from the disk 18, there being sufficient air drawn through the casing by the fan to maintain combustion.

15 There is not, however, sufficient air for complete combustion and a rich combustible mixture is formed by the sensible and radiant heat from the partial combustion of a portion of the sprayed fuel. The products of said combustion and vaporization pass downwardly through the inlet 22 into the fan, being mixed therein with 20

air from the inlet 21. The mixture is delivered through the grating 24 where it is ignited. After ignition is brought about above the grating 24, the portion of the burned gases directly beneath the collecting member 26 is drawn 25

therethrough into the casing 10. Said gases maintain the walls of the vaporizing chamber 11 in heated condition, thereby assisting in the vaporization of liquid fuel collecting thereon. The gases pass through the screen 12 which, as constructed in a working device, acts as a flame 30

dampener to extinguish flames from the burning gases passing into the member 26. The hot gases then pass into the vaporizing chamber 11 through the spray between the edge of the disk 35

18 and the adjacent wall of the chamber. The spray is at this point substantially all vaporized by the sensible heat of the hot products of complete combustion. As said gases are inert 40

there is no combustion at this point after the burner has been put into operation. The vaporization products continue to be drawn through 45

the inlet 22 of the fan housing. Said products are mixed with air from the outlet 21 sufficient for complete combustion and delivery through 50

the grating 24. It is to be understood that applicant has shown and described only a preferred embodiment of his improved liquid fuel vaporizer and burner and that he claims as his invention all modifications falling within the 55

scope of the appended claims.

What is claimed is:

1. A burner comprising a casing, a vaporizing chamber in said casing and spaced from the walls thereof, means for delivering liquid fuel 55

- in finely divided form to said chamber, a pump, means for delivering gaseous products from said chamber to said pump, means for delivering air to said pump, a burner grating, means for supplying gases from the pump to said grating, means in the vicinity of the grating on the flame side for collecting burned gases, said means being in communication with the casing, and means for delivering the burned gases from the casing to the vaporizing chamber. 5
2. A burner comprising a casing, a vaporizing chamber in said casing and spaced from the walls thereof, means for delivering liquid fuel in finely divided form to said chamber, a perforated member between the casing and the vaporizing chamber, a pump, means for delivering gaseous products from said chamber to said pump, means for delivering air to said pump, a burner grating, means for supplying gases from the pump to said grating, and means in the vicinity of the grating on the flame side for collecting burned gases, said means being 10 in communication with the casing for delivering the burned gases to the space between the casing and the vaporizing chamber, said gases thereby heating the vaporizing chamber through the walls prior to delivery into the chamber. 15
3. A burner comprising a casing, a vaporizing chamber in said casing and spaced from the walls thereof, said chamber being open at the top and in communication with the space between the chamber and the walls of the casing, means for delivering liquid fuel in finely divided form to said chamber, a pump means for delivering gaseous products from said chamber to 20 said pump, means for delivering air to said pump, a burner grating, means for supplying gases from the pump to said grating, and means in the vicinity of the grating on the flame side for collecting burned gases, said means being in communication with the casing being in communication with the casing. 25
